UNITED STATES PATENT OFFICE.

FRANK A. TUSTISON, OF MONTANA, KANSAS.

COMBINED CHAIR, CRIB, CRADLE, BED, AND WALKER.

SPECIFICATION forming part of Letters Patent No. 604,341, dated May 17, 1898.

Application filed May 12, 1897. Serial No. 636,223. (No model.)

To all whom it may concern:

Be it known that I, FRANK A. TUSTISON, a citizen of the United States, residing at Montana, in the county of Labette and State of 5 Kansas, have invented a new and useful Combined Chair, Crib, Cradle, Bed, and Walker, of which the following is a specification.

My invention relates to a convertible crib of which the parts are adapted to be adjusted 10 to form either a cradle, a chair, or a baby-tender, the chair or cradle body being adapted to swing; and the object in view is to provide a simple, efficient, and compact construction and arrangement of parts whereby the 15 changes necessary to adapt the device for the several uses mentioned may be accomplished with facility.

Further objects and advantages of this invention will appear in the following description, and the novel features thereof will be 20 particularly pointed out in the appended claims.

In the drawings, Figure 1 is a perspective view of a device embodying my invention adjusted for use as a chair. Fig. 2 is a similar view with the parts adjusted as a bed or cradle. Fig. 3 is a longitudinal section with the parts as illustrated in Fig. 1 and indicating in dotted lines the supporting-bars when in 25 their rearwardly-adjusted positions. Fig. 4 is a rear view to show the locking devices for the back. Fig. 5 is a detail view of one of the guard-plates detached. Fig. 6 is a similar view of one of the latches detached.

Similar numerals of reference indicate corresponding parts in all the figures of the drawings.

The frame of the device embodying my invention consists of corner-posts 1, connected 30 by upper and lower side rails 2 and 3 and upper and lower end rails 4 at one end and a single lower rail 5 at the other end, thus leaving the frame open at one end, which will be referred to hereinafter as the "rear" end, with 35 the exception of the single lower cross-bar 5. The corner-posts are provided with antifriction supporting rollers or casters 6, whereby when the device is in use as a baby-tender it may be readily moved.

50 Suspended within the frame is an adjustable chair structure having a seat 7, a back

8, and a foot-rest 9, the same being so connected as to be arranged either to form a chair, as illustrated in Fig. 1, or a bed-bottom, as shown in Fig. 2. This chair structure is 55 supported by swinging arms 10 and 11, the former of which are pivoted to the seat 7 and the latter to the back contiguous to its pivotal point of connection with the seat, and said swinging arms being pivotally connected 60 at their upper ends to horizontal supporting-bars 12, which rest upon the upper edges of the sides of the frame or upon the upper edges of the upper side bars. These supporting-bars are connected with the sides of the frame 65 by means of parallel links 13 and are capable of either forward or rearward adjustment, as shown, respectively, in full and dotted lines in Fig. 3, the former position being normal and adapting the device for use either as a 70 swinging chair, a cradle, or a crib. When the supporting-bars are adjusted rearwardly, as shown in dotted lines in Fig. 3, the device is adapted for use as a baby-tender in that the chair structure is moved sufficiently to 75 the rear to allow the occupant of the device to walk between the sides and closed end of the frame. A detachable handle 14, provided with a clasp, is also employed for imparting swinging movement to the chair 80 structure or bed-bottom, said clasp being adapted to engage either of the swinging arms, and a screen-guard 16 is employed to close the space between the upper and lower side bars and thus prevent the occupant of 85 the chair from injury by contact with the rounds 17, by which said bars are spaced.

From the above description it will be seen that the chair structure, comprising the seat, back, and foot-rest, constitutes a sectional bed-bottom which when the parts are arranged in a common plane, as illustrated in Fig. 2, is adapted to support the occupant of the device in a reclining position, and any suitable means may be employed for accomplishing 90 the adjustment of these sections of the chair structure to hold them in either their horizontal or any desired relative position. The preferred construction embodies side arms 18, connecting the back-section at an intermediate point with the upper extremities of foot-rest arms 19, said foot-rest arms being pivot- 100

- ally mounted upon the seat-sections, in connection with locking devices for securing the back-section at the desired inclination with relation to the seat-section. I preferably attach perforated segments 20 to the seat-section concentric with the pivotal point of connection of the back-section therewith, and mount spring-actuated latches 21 on the back-section, said latches having bolts 22 to engage the perforations of the segments. In the construction illustrated these latches are connected by a coiled actuating-spring 23, whereby they are yieldingly held in operative relation with the segments. Operating-levers 24 are also pivotally mounted upon the back-section contiguous to its top and are connected by rods or wires 25 with the latches, whereby the movement of the operating-levers toward each other, as by opposite pressure applied by the thumb and finger thereto, serves to withdraw the latches from the segments and allow the back to be adjusted. The latches are preferably mounted upon guard-plates 26, having guides 27, which embrace the segments, and also having perforated ears 28, through which the bolts of the latches operate. Furthermore, the operating-levers are provided with inner and outer stops 29 and 30.
- 30 The occupant of the swinging member of the device may impart an oscillatory movement thereto by periodical pressure applied to the foot or closed end of the frame; but when it is desirable to operate said swinging member exteriorly, as by an attendant, the handle 14 is applied to either of the swinging arms to suit the convenience of the operator. Furthermore, it will be seen that as the front and rear swinging arms are pivotally connected at their lower ends respectively to the seat and back sections the arrangement of the back and foot sections of the chair structure in a horizontal position will dispose the seat-section in a corresponding and common plane therewith, whereas the arrangement of the back and foot sections at an inclination to the seat-section to form a chair will allow the rear edge of the seat-section to drop slightly below the plane of its front edge and thereby incline the seat-section downwardly toward its rear edge, thus giving greater comfort to the occupant of the chair than if the seat-section were maintained in a horizontal position.
- 55 Various changes in the form, proportion, and the minor details of construction may be resorted to without departing from the spirit or sacrificing any of the advantages of this invention.
- 60 Having described my invention, what I claim is—
1. The combination of a frame a chair structure suspended within the frame by swinging arms, and adjustable connections between the swinging arms and the frame, whereby the chair structure may be adjusted

longitudinally of the frame, substantially as specified.

2. The combination of a frame having anti-friction supporting devices, a chair structure suspended within the frame by swinging arms, and adjustable connections between the swinging arms and the frame whereby the chair structure may be adjusted longitudinally of the frame, substantially as specified. 75

3. The combination of a frame, supporting-bars mounted upon the frame for adjustment longitudinally thereof, swinging arms carried by the supporting-bars, and means for supporting an occupant suspended by said swing-ing arms, substantially as specified.

4. The combination of a supporting-frame, a sectional chair structure suspended for swinging movement within and longitudinally of the frame, and means for securing 85 the sections of the chair structure in the desired relative positions, substantially as speci-fied.

5. The combination of a supporting-frame, supporting-bars resting upon the upper edges 90 of the sides of the frame, links connecting the supporting-bars with the frame, whereby the supporting-bars may be adjusted longitudinally of the same, swinging links sus-pended from the supporting-bars, and a sec- 95 tional chair structure supported by the swing-ing arms, substantially as specified.

6. The combination with a supporting-frame, of side swinging arms pivotally mounted at their upper ends on the frame, an occu-pant-supporting device suspended by said swinging arms within the frame, and an operating-handle provided with a clasp con-structed to fit upon and detachably engage the upper end of one of said swinging arms, 105 whereby oscillatory motion may be imparted to the occupant-supporting device by an at-tendant, substantially as specified.

7. The combination with a supporting-frame, of a sectional chair structure suspend-ed by swinging arms within said frame, and including a seat-section, a foot-section having arms pivotally mounted upon the seat-section, a back-section pivotally mounted upon the seat-section, side arms connecting the 115 back-section with the upper extremities of the arms of the foot-section, perforated seg-ments carried by the seat-section, spring-actuated latches pivotally mounted upon the back-section to engage the perforations of said 120 segments, and contiguous bell-crank operating-levers 24 mounted upon the back-section at its upper end and respectively connected by independent means with said latches, sub-stantially as specified. 125

8. The combination with a supporting-frame, of a sectional chair structure having pivotally-connected seat, back and foot sec-tions, and means for securing the same at the desired relative adjustment, and spaced front 130 and rear swinging arms supported at their upper ends with the said frame and pivot-

ally connected at their lower ends respectively to the seat near its front edge and the back-section near its pivotal connection with the seat, whereby when the back and foot sections are adjusted at an inclination to the seat-section, the rear edge of the seat-section is depressed below its front edge, substantially as specified.

In testimony that I claim the foregoing as my own I have hereto affixed my signature in 10 the presence of two witnesses.

FRANK A. TUSTISON.
